UNITED STATES PATENT OFFICE.

GEORGE E. TITCOMB, OF PHILADELPHIA, PENNSYLVANIA, ASSIGNOR, BY MESNE ASSIGNMENTS, TO LINK-BELT COMPANY, OF CHICAGO, ILLINOIS, A CORPORATION OF ILLINOIS.

CHARGING RAILWAY SYSTEM.

1,140,214.

Specification of Letters Patent. Patented May 18, 1915.

Application filed February 17, 1911. Serial No. 609,126.

To all whom it may concern:

Be it known that I, GEORGE E. TITCOMB, a citizen of the United States, residing in Philadelphia, Pennsylvania, have invented 5 certain Improvements in Charging Railway Systems, of which the following is a specification.

In plants of the type to which my invention relates there is a central bin on each 10 side of which is a series of coke ovens and there is a gas outlet at the center of each oven, communicating with a main so that the coal must be discharged into the ovens on each side of the gas outlet. This necessitates, in large ovens, the use of two independent tracks on which the lorries or cars 15 travel so as to convey the coal from the lorry bins to the different coke ovens.

The object of the present invention is to 20 provide means for driving a car on each track from one car so that only one motorman is required to handle both cars.

In the accompanying drawings;—Figure 1, is an end view showing the coke ovens 25 and the lorries or transfer cars located above the ovens; Fig. 2, is a view showing the lorries or transfer cars located under the lorry bin; Fig. 3, is a plan view of one of the transfer cars; Fig. 4, is an end view of 30 the car shown in Fig. 3; Fig. 5, is a diagram plan view of the plant, and Fig. 6, is a diagram illustrating the electric wiring by which the two cars are controlled by a motorman on one of the cars.

Referring in the first instance to the diagram Fig. 5, A is the lorry bin of sufficient 35 size to store a quantity of coal. B—B are the coke ovens mounted on each side of the lorry bin and over the series of ovens are 40 located the tracks C—C on which the cars D travel in conveying the coal from the lorry bin to one of the series of ovens. Extending through the roof of each bin at a point midway between the sides of the ovens 45 is a gas pipe B' which communicates with the gas main B², and at each side of the coke ovens are doors b—b, which are closed during the coking process and opened when the coke is to be discharged. These doors 50 can be operated by independent mechanism, if desired, but I prefer to operate them from the mechanism on the cars as described hereafter. The location of the several gas pipes at the center of the coke ovens necessi- 55 tates the use of two tracks C—C', one track

being located above the ovens on one side of the series of gas pipes and the other track being located on the opposite side, as clearly shown in the drawings. Consequently, two cars D—D' are necessary for the proper 60 charging of the coke ovens with coal and as the charging should be done at the same time both cars must be loaded and driven simultaneously. If the cars were electrically driven in the ordinary manner, this would 65 necessitate two sets of electric mechanism on each car and two motormen or drivers, but by my invention I am enabled to dispense with the service of one motorman and to drive both cars from a point on one car, 70 not only reducing the cost of operation, but making easily possible the simultaneous movement of the cars and the simultaneous discharge of the coal into the ovens. The lorry bin A is provided with six discharge 75 spouts a in the present instance the discharge of coal being controlled by valves or gates a' operated in any suitable manner and the lorry cars are each provided with three spouts d having valves or gates d' 80 (Fig. 4). These valves d' are in the form of sliding plates which are connected to arms on a rock shaft d² mounted on each car, on the rock shaft is a hand lever d³ by which it is turned. The valves may be op- 85 erated simultaneously in any other suitable manner so as to quickly discharge the coke into the oven. The oven has a series of openings b' through which the coal is dis- charged from the cars. These openings are 90 closed by ordinary cover plates or valves. A vertically movable sleeve d⁴ surrounds each spout and is raised and lowered by lever mechanism connected to the shaft d² so that when the valve or gates d' are with- 95 drawn the sleeve is lowered, closing the space between the spout and the openings b' in the ovens. i—i are the main feed wires from which the current is obtained to operate both cars and i', i², i³, i⁴, are connecting 100 wires or rails extending adjacent both sets of tracks C. Trolley poles (not shown) are mounted on the cars D—D' for conveying current to and from the two controllers I—I' and between the controller I' and the motor m'—N². The controller I governs the motor N on the car D, while the controller I' gov- 105 erns a similar motor on the car D'. k is the resistance for each controller and N' is the field for the motor on the car D and N² is 110

the field for the motor on the car D'. m—m' are the armatures and s—s' are the solenoid brakes, so that one operator located on one car can govern movement of both 5 cars by the use of the controllers I—I'. Thus, by operating the handle to the controller I, the motor m—N' may be started and brought up to speed as the resistance k is cut out of circuit, thereby causing the car 10 D to be operated to any desired position. Similarly, the operation of the controller I' causes current to be delivered from the feed 15 mains i—i to the connecting wires i', i², i³, i⁴, and thence to the motor m'—N². Obviously both controllers include means for reversing their respective motors.

The arrangement of the mechanism may be varied according to the type of car used. In the present instance, referring to Figs. 20 3 and 4, e—e' are the wheels mounted on the axles E—E' of the cars D. The axle E is the driven axle, driven from the shaft F through the medium of gears f and e². N is the motor. The armature shaft M of this 25 motor is geared to the shaft F through gearings f'—f². In order to operate the doors b—b² of the oven over which the cars D—D' are located, I provide a motor G on each car and this motor is geared by a worm g and worm wheel g' to a driven shaft G' on 30 which is a drum g²; a rope or chain H extends from the drum and around a sheave h on a frame carried by the car, and the rope has a hook h' at its free end to engage an 35 eye on the door b (Fig. 1) so that when the hooks are coupled to the doors and the motors started through the controller I² both doors of the ovens will be raised so that a pusher can enter the oven to push out the 40 finished coke, or a device may be inserted to level the coke in the oven before cooking. In some instances the door operating mechanism of the two cars may be independent of one another. Then there will be a controller 45 I² on each car.

In operation it will be seen that the lorry bins are charged with coal by any suitable

mechanism and the lorry cars are loaded simultaneously from the bin. Then, as soon as the cars are charged and the doors are 50 closed, the operator, through the medium of the two controllers I—I', traverses the cars over the tracks simultaneously and when the cars are over the openings of a particular bin the valves or gates d' in the bottom of 55 the cars are opened and the coal flows from the cars through the openings directly into the oven; the coke charge having been previously removed. Preferably, while the cars are located over the oven and before they 60 are discharged, the hooks h' of the hoisting chains H engage the eyes on the doors b of the oven and the mechanism controlling the drum shafts is operated, causing the chain to wrap around the drum g² and lift the 65 doors. While the doors are in the raised position a discharging apparatus enters the oven at one side and pushes the coke out of the oven at the opposite side. When this discharging apparatus is removed the doors 70 are lowered and the gates of the cars are opened, allowing the coal to flow directly into the oven and when the charge has been completed suitable mechanism can be used to level the charge, if necessary. After the 75 coal is discharged from the cars the mechanism is operated so as to traverse the cars back to a position under the lorry bins, where a fresh supply of coal is obtained for another oven. 80

I claim:

The combination of two tracks; a car arranged to travel on each track; electric mechanism for driving the cars; and two controllers mounted on one car for controlling the movement of both cars. 85

In testimony whereof, I have signed my name to this specification, in the presence of two subscribing witnesses.

GEORGE E. TITCOMB.
